[57] CLAIM

The ornamental design for a paint brush cleaning tool, as
shown and described.

DESCRIPTION

FIG. 1 is a perspective view of a paint brush cleaning tool
showing my new design;

FIG. 2 is an elevation view of one side thereof, the opposite
side being a mirror image;

FIG. 3 is a top plan view thereof;

FIG. 4 is a bottom plan view thereof;

FIG. 5 is an elevational view of the right end thereof; and,

FIG. 6 is an elevational view of the left end thereof.
